UNITED STATES PATENT OFFICE.

GEORGE W. MOSEY AND CLARENCE K. MOSEY, OF SEATTLE, WASHINGTON.

VALVE-TAPPET SILENCER.

Application filed May 10, 1921. Serial No. 468,456.

To all whom it may concern:

Be it known that we, GEORGE W. MOSEY and CLARENCE K. MOSEY, citizens of the United States, and residents of Seattle, county of King, and State of Washington, have invented a new and useful Valve-Tappet Silencer, of which the following is a specification.

Our invention relates in general to internal combustion engines of the poppet valve type and has reference more particularly to an improved silencer for the valve tappets therefor.

In various types of valve tappets and especially those used for the so-called overhead valves, as commonly used in certain types of motor vehicle engines, the push rods are connected to the tappets by curved plates which confine the ends of the rods and tappets in confronting relation so that the tappet may impart a push to the push rod when actuated by the cam shaft. These curved plates act in reality as guides in that they do not rigidly connect the rods and tappets; in other words there is a slight play between them, and this looseness, together with the loose coupling for the curved guide plates, results in considerable noise when the engine is running.

While it is possible to prevent this noise to a certain extent by adjustments in the rods, this does not entirely overcome the same; then again such adjustments do not hold and in a short time the same undesirable noisy conditions are present. The primary object of our invention is to provide simple and inexpensive means to relieve this noisy condition and further to so construct the silencing means that it may be readily incorporated in the engine structure without necessarily changing the engine to accommodate the same.

The invention possesses further features which will appear as the description of the invention proceeds with reference to the illustrative embodiments shown in the accompanying drawing. In said drawing Figure 1 is a horizontal section of an internal combustion engine on the line 1—1, Figure 2, and showing the application of the invention; Figure 2 is a cross-section on the line 2—2 Figure 1; Figure 3 is a detail plan view of the silencer; Figure 4 is a front view of the housing for the silencer blocks and Figure 5 is a detail perspective view of one of the silencer blocks.

Referring now to the drawing in detail (1) represents an internal combustion engine, which, for the purpose of illustrating one adaptation of the invention, may be considered as having four cylinders and using the overhead type of valves. Each valve will employ a push rod (2) which extends through the overhang (3) of the engine to contact with one end of a rocker (not shown) which is directly associated with its respective valve stem. The lower and opposite end of the push rod (2) terminates with screw threads and the same is threaded into a sleeve (4) which is slotted longitudinally so that the sleeve may be joined to the tappet by a curved guide plate (5). As best shown in Figure 1 these curved guide plates include inwardly bent parallel ends arranged in confronting relation so that they may engage the slots of the sleeve (4) as well as similar slots in the tappet (6) which contacts directly with the cam shaft.

As above mentioned this construction makes considerable noise and to overcome the same we propose to employ fibre or the like cushioning blocks (7), one block for each pair of tappets for one cylinder. Each of these blocks may be made in rectangular form with the outer side edge notched as at (8) to accommodate the two push rods so that the straight edges on both sides of the notches (8) will leave flat bearing faces to abut against the faces of the inwardly presented ends of the guide plates (5).

As a convenient means of mounting the blocks (7) we propose to employ one housing cage (9) for each two of the blocks. This cage may be constructed of sheet metal and having top, bottom, back and end walls and leaving an open front. A middle partition (10) is used to divide the cage into two compartments, one for each one of the blocks. The cages are mounted upon a shelf (11) of the engine casting in back of the tappets with their inner ends in juxtaposition and with the rods (12) threaded into the partitions (10) holding the same securely fixed to the engine block. The outer ends of the cages may be properly confined by outwardly presented wings (13) on the sides of the first and last cylinders. In practice the blocks (7) should be maintained against the curved guide plates preferably under pressure; therefore we prefer to employ a series of coiled springs (14), two springs for each of the blocks (7). These springs

are anchored or seated at one end in seats (15) in the back of the compartments of the cages and in the ends thereof. The opposite ends of the springs abut against the inside 5 edge of the blocks with notches in the blocks receiving the same.

The influence of these springs will press the blocks outwardly and hold them in contact with the guide plates. To limit the 10 action of the springs, pins (16) are carried by the cages with slits (17) in the blocks in which the pins are received.

From the above it will be seen that the 15 tappets and their associated parts are under constant influence of the blocks (7) which will overcome the customary noisy operation of this part of the engine. The blocks act not only to steady the tappets and the push rods at their contacting ends but 20 they also act in the capacity of an absorbing or cushioning medium for vibration and a noise deadener.

The details of construction referred to in 25 the drawing and throughout the specification should be considered only as an example of one way the invention may be reduced to practice, as certain changes may be required to adapt the arrangement to various types 30 of engine constructions.

We claim:

1. A valve tappet silencing device for 35 internal combustion engines comprising means mounted behind the valve tappets in constant contact therewith and spring means for maintaining said contact.

2. A valve tappet silencing device for 40 internal combustion engines comprising a block mounted behind the valve tappets in constant contact therewith and spring means for maintaining said contact.

3. A valve tappet silencing device for 45 internal combustion engines comprising a block mounted behind the valve tappets in

constant contact therewith and spring means 45 for maintaining said contact, said block and spring means being confined within a cage which in turn is rigidly fixed to the engine casting.

4. A valve tappet silencing device for 50 internal combustion engines comprising a block mounted behind each two of the valve tappets and in contact therewith, a confining cage divided to form a separate compartment for each of a pair of blocks and spring means in each compartment of the confining 55 cages for maintaining a constant contact of the blocks with the valve tappets.

5. A valve tappet silencing device for 60 internal combustion engines comprising a block mounted behind each two of the valve tappets and in contact therewith, a confining cage divided to form a separate compartment for each of a pair of blocks and spring means in each compartment of the confining 65 cages for maintaining a constant contact of the blocks with the valve tappets, said confining cages being rigidly fixed to the engine casting and including means for limiting the influence of the spring means relative to 70 the blocks.

6. A valve tappet silencing device for 75 internal combustion engines comprising an oblong fibre block mounted behind each two of the valve tappets and in contact therewith, each of the blocks having notches cut 80 in one of their plane surfaces to partly encircle the valve tappets, a confining cage for each two of the blocks, said cages including a separate compartment for each block, springs in said compartments behind said blocks adapted to maintain the blocks in constant contact with the valve tappets, and means for restricting the influence of said springs.

GEORGE W. MOSEY.
CLARENCE K. MOSEY.
